(57) **CLAIM**

The ornamental design for an infrared heating apparatus, as shown and described.

DESCRIPTION

FIG. 1 is a perspective view of an infrared heating apparatus showing my new design.

FIG. 2 is a left side elevational view thereof.

FIG. 3 is a right side elevational view thereof.

FIG. 4 is a top view thereof.

FIG. 5 is a rear view thereof.

FIG. 6 is a bottom view thereof; and,

FIG. 7 is a front view thereof.

The broken lines shown in the drawings are for the purpose of illustrating environmental structure and form no part of the claimed design.
